UNITED STATES PATENT OFFICE

144,722

DESIGN FOR AN ELECTRIC HEATER

Hugh G. Landis, deceased, late of Los Angeles,
Calif., by Bess S. Landis, executrix, Los Angeles,
Calif.

Application August 17, 1945, Serial No. 121,443

Term of patent 7 years

(Cl. D81—10)

To all whom it may concern:

Be it known that I, Bess S. Landis, a citizen of the United States of America, residing in the city of Los Angeles, in the county of Los Angeles, State of California, am executrix of the last will and testament of Hugh G. Landis, late a citizen of the United States of America residing at 1738 West 43rd Place, Los Angeles, California, deceased, who has invented, a new, original, and ornamental Design for an Electric Heater, of which the following is a specification, reference being had to the accompanying drawing, forming a part thereof.

Fig. 1 is a front elevational view of an electric heater showing the new design;

Fig. 2 is an end elevational view of the same;

Fig. 3 is a rear elevational view; and

Fig. 4 is a top plan view thereof.

It is claimed:

The ornamental design for an electric heater, substantially as shown.

BESS S. LANDIS,

Executrix of the Estate of Hugh G. Landis, Deceased.
